UNITED STATES PATENT OFFICE.

FERDINAND MANTE, OF ST. LOUIS, MISSOURI.

CAMP-TABLE.

1,323,080.

Specification of Letters Patent. Patented Nov. 25, 1919.

Application filed February 27, 1917. Serial No. 151,313

To all whom it may concern:

Be it known that I, FERDINAND MANTE, a citizen of the United States, residing at St. Louis, State of Missouri, have invented new 5 and useful Improvements in Camp-Tables, of which the following is a specification.

The present invention relates to tables, and more particularly to that class thereunder known as foldable camp tables, designed 10 primarily for use by campers, automobilists, canoeists, and the like parties, and one which may be conveniently and expeditiously folded into compact structure, thus occupying but a minimum amount of space in the 15 storage or transportation of the same.

The invention is directed more specifically to a table top structure and is designed primarily as an improvement on my prior Patent No. 1,226,554 granted to me under date 20 of May 15, 1917.

The primary object of the invention resides in the production of a table of this character wherein novel means are employed for locking the table top in an open or extended 25 position for preventing the accidental folding of the top within the tube.

Furthermore, I contemplate, among other features, the provision of a table top embodying a plurality of radially extending 30 arms, and an adjustable member associated with each of the arms and to which the covering of the table top is connected, for permitting the covering to be stretched to assume a taut position at all times, which from 35 the actual use of the device, I have found necessary, owing to the different climatic conditions.

With the above and other objects in view, the invention consists in the novel features, 40 details of construction and combination of parts which will hereinafter be more fully set forth, illustrated in the accompanying drawings and pointed out in the appended claims.

45 Figure 1 is a view in elevation of a folding table constructed in accordance with the present invention, the parts being shown in open position;

Fig. 2 is a similar view showing the table 50 folded;

Fig. 3 is a longitudinal sectional view;

Fig. 4 is a section taken on line 4—4 of Fig. 1.

Fig. 5 is a section taken on line 5—5 of 55 Fig. 1.

Fig. 6 is a section taken on line 6—6 of Fig. 8.

Fig. 7 is a plan view of the connecting means for the covering; and

Fig. 8 is a bottom plan view of the top 60 illustrating the top forming parts in a locked open position.

Referring more particularly to the accompanying drawings, in which like characters of reference refer to corresponding parts in 65 the several views, the table comprises a tubular body portion 6 forming the pedestal of the table in the active position of the same, and forming a tube into which the various parts constituting the table construction are 70 inserted when the table is in folded or compact form. This body portion or tube 6 is of suitable length and diameter having hinged to the ends thereof covers 7—7 75 adapted to close the ends of the tube. A handle 8 is connected to the tube at a point intermediate its ends. Arranged within the tube at a point centrally of the distance between its ends is a ring 9 secured within the tube, while arranged in the outer ends of 80 the tube and suitably secured therein are outer rings 10. Slidably mounted within the tube between the center ring 9 and the outer rings 10 are disks 11 and 12, the inner ring 9 serving to limit the inward movement of the disks 11 and 12 respectively, while the outer rings 10 serve to limit the 85 outward movement of the disks.

The disk 11 has connected therewith the support forming members which in this particular instance consists of legs 13 swingingly mounted on pivot wires 14, and having their innermost ends projected in openings 15 formed in the disk 11. A suitable spider 16 is detachably connected to the inner face of the disk through the employment of fasteners 17, and this spider is stamped to provide therein grooves 18 and 19 respectively. The grooves 18 accommodate the pivot wires 14, while the grooves 19 100 have inserted therein one extremity of the coiled springs 20, such springs being designed to swing the legs to active position and to hold the same against folding movement, by coiling the opposite end of the 105 spring around the pivot wires and positioning its extremity within the ends of the legs 13.

The disk 12 is primarily intended to connect the top structure with the tubular body 110

6, and to this end, the said disk is provided with an annular flange 21, and secured in any suitable manner to the inner circumference of this flange are a plurality of pairs 5 of spaced concentrically arranged bearings 22 through which the pivot wire 23 passes intersecting the spaces 24 formed by the specific arrangement of the bearings 22. A hub 25 is formed centrally of the inner face 10 of the disk 12 and in spaced relation with the confronting surfaces of the spaced bearings 22. The purpose of such hub will be fully set forth as the description of the invention is proceeded with. The top forming 15 members are shown as an annular series of spaced channeled arms 27 pivotally connected in the spaces 24 between the bearings 22 and on the pivot wire 23 for an outward swinging movement, when it is desired to 20 open the table top for use. The top wall 28 of each of the channel arms is provided with a plurality of longitudinally arranged slots 29 for connecting to each of the arms for longitudinal adjustment, through the medium 25 of a bolt and nut fastener 30, metallic binding strips 31 to which is connected the flexible covering or top 32. By this construction, it will be manifest that should the flexible covering become loose owing to 30 climatic conditions, the same may be stretched or tightened by the adjustment of the binder strips 31 longitudinally of the radial channel shaped arms 27.

Another essential characteristic of this 35 invention, in addition to the stretching means for the flexible top 32 resides in the locking means for holding the radial arms 27 against folding movement. This locking element constitutes a rotatable plate 34 connected to the bottom of the hub 25 by a plurality of spaced studs 35 secured to and depending from the hub 25 and projecting through the arcuate slots 36. Rotary movement is imparted to this locking element 34 40 by inserting a key, not shown, through a centrally formed opening in the hub 25 registering with an angular opening 37, formed in the plate 34. In accomplishing the object sought, use is made of a plurality of

spaced concentrically arranged L-shaped lugs 38 formed on the extreme marginal 50 edge of the plate 34 and upon imparting movement to the plate for locking the radially extending arms 27 in a horizontal position, the plate rotates substantially 15°, bringing the lugs 38 under the closed ends 55 39 of the arms 27, consequently preventing the arms from folding in an upward direction and avoiding accidental folding of the top structure within the tubular body 6.

From the foregoing description, taken in connection with the accompanying drawings, the advantages of construction and the method of operation will be readily apparent to those skilled in the art to which the invention relates, and while I have described the principles of operation of the invention, together with the device which I now consider to be the best embodiment thereof, I desire to have it understood that the device shown is merely illustrative, and that such changes may be made when desired as are within the scope of the appended claims.

What is claimed as new, is:

1. A table top construction comprising a 75 disk provided with spaced bearings, an annular pivot passing through said bearings, a plurality of arms pivotally mounted between said bearings and on said pivot, a rotatable locking member carried by the disk, 80 and a plurality of L-shaped lugs formed on the periphery of said disk.

2. A table top construction comprising a disk provided with spaced bearings, a plurality of channel arms provided at points adjacent their inner ends with openings, an annular pivot passing through the bearings of the disk and the openings of the channel arms of pivotally mounting the channel arms to said disk and a rotatable locking 90 member carried by the disk and disposed inwardly of and in spaced relation with the pivoted member for locking the channel arms in active position.

In testimony whereof I affix my signature. 95

FERDINAND MANTE.
